LOCK FOR THE COVERS OF ROTATING TANKS

Charles W. Bruger, Union City, N. J.

Application July 2, 1932. Serial No. 620,572

2 Claims. (Cl. 210—63)

This invention relates to improvements in locking devices, particularly to locks for the covers of rotating tanks in laundries or dye-works, etc., and it is the principal object of my invention to provide a lock for the covers of said tanks which can be opened only when the tank is at rest and positively preventing an opening of the lock and cover while the tank is rotating to avoid accidents.

Another object of my invention is the provision of a lock of this type equipped with a pendulum bar which during the rotation of the tank assumes an inclined position and which permits an opening of the tank and its cover only when it is in a strictly vertical position, i. e. when the tank comes to a perfect standstill and the pendulum bar is engaging the inner upper rim of the tank at a right angle.

Still another object of my invention is the provision of a lock the operating lever of which can retract the lock bolts from its keeper only when supported by a support at rest to operate said bolt by the intermediary of a rack and gear mechanism actuating a retracting link for said bolt.

A further object of my invention is the provision of a lock for the cover of rotating tanks permitting their opening only when the tank is at a standstill to allow the operation of a movable member having a depending finger to engage abutments formed on the lock bolt to disengage the same from its keeper.

A still further object of my invention is the provision of a locking means for the covers of rotating tanks of simple and inexpensive construction, yet durable and highly efficient in operation.

These and other objects and advantages of my invention will become more fully known as the description thereof proceeds and will then be specifically defined in the appended claims.

In the accompanying drawings forming a material part of this disclosure:

Fig. 1 is a side elevation of a tank and its basket partly in section, and equipped with a lock constructed according to my invention.

Fig. 2 is a sectional top plan view of the lock.

Fig. 3 is a side elevation of the lock after removal of its front cover plate.

Fig. 4 is a cross-section on line 4—4 of Figure 3.

Fig. 5 is a perspective detail view of the locking bolt and cooperating parts.

As illustrated, in Figures 1 to 5, a tank 10 as they are for instance used in laundries, dyeing

establishments or the like, is rotated by means of a belt 11 from any suitable motor and has a discharge valve 12.

Within this tank a basket 13 having a plurality of openings 14 is provided, the upper edge of which is equipped with an inwardly directed annular flange 15.

The tank and basket are covered by a cover 16 hinged to the tank as at 17 and carrying a keeper 18 at a point oppositely disposed to hinge 17.

The keeper is adapted to be engaged by the bolt 19 of a lock within a casing 20 on the tank.

The lock comprises a back-plate 21 provided with a foot bracket 22 for securing the plate and casing 20, to a support. The rear part of bolt 19 has an offset part 23 by means of which the bolt is guided for horizontal reciprocation in a longitudinal groove 24 in the back plate 21.

A longitudinally extending bore 25 in bolt 19 is adapted to guide a bolt 26 therein, the movements of which are controlled by a spring 27 in said bore and latch or bolt 19 is moved between the guide screws 28, 29, and 30.

A pin 31 projects from the front face of bolt 19 and is adapted to engage a substantially V-shaped notch 32 in a member 33 secured by means of a screw 34 to the back-plate.

The shank of screw 34 carries rotatably therein a gear 35 in mesh with the teeth of a rack bar 36 arranged for vertical reciprocation in a groove 37 of the rear plate.

To the lower reduced end 38 of bar 36 is pivotally attached by means of a screw 39 an operating lever 40 having a knee 41 formed intermediate its ends. The outer end of lever 40 is formed into a handle 42 while its inner end is equipped with a stud 43 projecting therefrom, to which is movably attached the upper suitably bored end of a pendulum bar 44 prevented from slipping off the pin by means of pin 45.

Rack bar 36 is guided by a screw 46, and the movements of the operating lever 40 are controlled by a spring 47 secured at one end to a pin 48 projecting from the back plate and anchored with its other end in a recess 49 in the handle part of operating lever 40. The inner face of the handle 42 forming the knee 41 is at its lower part somewhat bevelled, as at 50.

The upper end of the pendulum bar engages in a recess in the lower front part of the back plate having its rear wall 50' formed on a slant.

In operation, the bolts 19 and 53 are normally engaged with their keepers 18 and the pendulum bars 44 and 72 loosely suspended from their pins 43, 71, respectively, during the rotation of the

inner basket 13, if they are depressed by means of handles 42, 70, in an attempt to open the lock will glide along in an inclined position on the upper inner flange 15 of the basket so that the operating bar will not find sufficient support to actuate the locking bars, and the locks cannot be opened. As soon, however, as the basket comes to a standstill or rest, the pendulum bars 44, 72, will be vertically engaged with flange 15 at a right angle 10 and the operating handles will find sufficient support to open the locks, in the form illustrated in Figures 1 to 5 by lifting rack bar 35 to operate gear 35 to operate lock 33, the inward movement of which is limited by screw 30 to engage pin 15 31 in its notch 32 and draw bolt 19 inwardly out of engagement with its keeper.

It will be understood that I have described and shown the preferred forms of my invention only as examples of the many possible ways to practically construct the same, and that I may make such changes in the general arrangement of the locks and in the construction of their minor details as come within the scope of the appended claims without departure from the spirit of my 25 invention and the principles involved.

Having thus described my invention what I claim as new and desire to secure by Letters Patent, is:

1. A rotating tank, a basket therein and a cover for said basket and tank hinged thereto at one end, and locking means for said cover comprising a spring controlled bolt, a pin on said bolt, a member pivoted at its upper end and having a substantially V-shaped notch for engagement by the pin of said bolt, a pin for limiting the inward movement of said member, a gear on

the pivot of said member, a rack displaceably arranged in said lock, the teeth of which are in mesh with said gear, an operating lever attached to said rack, a pendulum movably connected with said lever constituting a support for the same as soon as the tank comes to a standstill to lift said rack for operating said gear to engage said pin in the notch of said member for drawing the bolt in its unlocking position. 80

2. A rotating tank, a basket therein and a cover for said basket and tank hinged thereto at one end, and locking means for said cover comprising a casing, a back-plate on said casing having a groove, a bolt having a rear flange slidably arranged in the groove of said back-plate, a pin projecting from the side of said bolt, a spring controlled pin on the inner end of said bolt, guides for said bolt during its sliding motion, an operating lever having an outer handle and a knee pivoted intermediate its ends, a rack bar vertically displaceable in a groove of said back-plate, a gear in mesh with the teeth of said rack for engaging and disengaging the notch of a movable member with the side pin of said bolt, and a pendulum loosely connected to the inner 90 end of said operating lever to form a support as soon as the tank comes to a standstill for supporting said lever for allowing its operation to the handle to lift said rack bar and rotating said gear to engage the notch of said member with 95 said side pin of the bolt to draw the bolt into its unlocking position, and means to retain the parts in their normal position after each operation. 100
